DESIGN FOR A COMBINED VENDING, WEIGHING, AND ADVERTISING DE- VICE

Guy G. Eidman, Houston, Tex.

Application June 9, 1934, Serial No. 52,122

Term of patent 14 years

To all whom it may concern:

Be it known that I, GUY G. EIDMAN, a citizen of the United States, and residing at Houston, in the county of Harris, and State of Texas, have invented a new, original, and ornamental Design for a Combined Vending, Weighing, and Advertising Device, of which the following is a specification, reference being made to the accompanying drawing, forming a part thereof:

In the accompanying drawing, Fig. 1 is a front elevation of the device; and Fig. 2 is a side elevation thereof.

I claim:

The ornamental design for a combined vending, weighing and advertising device, substantially as shown.

GUY G. EIDMAN.
